UNITED STATES PATENT OFFICE.

LEANDER P. BOWEN AND WILLIAM J. WHITE, OF AUBURN, NEW YORK.

APPARATUS FOR DRYING THE FACE.

SPECIFICATION forming part of Letters Patent No. 783,606, dated February 28, 1905.

Application filed June 11, 1900. Serial No. 19,896.

To all whom it may concern:

Be it known that we, LEANDER P. BOWEN and WILLIAM J. WHITE, of Auburn, in the county of Cayuga, in the State of New York, have 5 invented new and useful Improvements in Apparatus for Drying the Face, of which the following, taken in connection with the accompanying drawings, is a full, clear, and exact description.

10 This invention relates to improvements in barbers' supplies, having more particular reference to means for drying the face after it has been shaved and after it has been bathed with toilet preparations, such as bay-rum, 15 witch-hazel, and the like.

After the barber has bathed the face subsequent to shaving it is the usual practice to dry it by the use of a fan or the vibration of a towel or by other means equally as inconvenient.

One object of our invention is to construct a device by which an air-blast may be thrown or projected upon the face, and which device may be easily, readily, and conveniently attached to any chair, and which is cheap and durable in its construction and of great utility.

To that end our invention consists in the several new and novel features of construction and combination of parts hereinafter described, 30 and specifically set forth in the appended claim.

In describing the invention in detail reference will be had to the accompanying drawings, showing an embodiment of our invention, 35 and in which--

Figure 1 is an isometrical view of a barber's chair, showing our improvement attached thereto and ready for operation. Fig. 2 is a detached perspective view of the pump or air-forcing apparatus, showing it mounted upon a bracket and provided with a foot-operating piece. Fig. 3 is a vertical section through the pump or air-forcing apparatus, the operating-rod being broken away.

40 In the drawings, A is a barber's chair, which may be constructed in any manner desired, either elaborate or simple. In view of the fact that our invention does not relate to the chair, but only to the attachment thereto, it 45 will be evident that the form and construc-

tion of the chair is immaterial. Beneath the chair or at any other point which may be convenient according to the type of chair we mount a bracket *a* *g*, which has arms *a*' *a*'''. The arm *a*' may be braced, as at *b*', if desired, 55 and is secured to the upper and stationary head of the cylinder *b* of the pump or air-forcing apparatus. The cylinder of the pump or air-forcing apparatus is provided with a stationary upper head and a movable lower 60 head. The stationary upper head may be provided with an opening *c*, kept normally closed by means of a plug *c*', and the lower or movable head has an exit *d*, to which is connected a tube *e*, as shown in Fig. 1. This tube may 65 be held in any convenient manner on the back of the chair when not in use and as fully illustrated in Fig. 1. The lower or movable head *c*'' is actuated to compress the air and force the same into tube *e* by means of a rod 70 *f*, connected at its lower end to a foot-lever *f*'. The rod *f* passes through the arms *a*'' *g*, and these arms serve to guide and support said rod. The rod *f* is pinned or otherwise suitably connected at its upper end to a member 75 or cross-head *f*'', separated from and connected to the bottom or lower head *c*'' by pins *d*', so as to leave a free passage for the air through the opening *e*' in the lower head *c*''. This opening is closed during the ascent of the lower 80 head *c*'' by a flap-valve *v*'', carried on the upper face of said lower head, and a spring *h*, arranged between the upper and lower heads of the pump-cylinder, accelerates the return of the lower head to its normal or lower position. In some instances it is desirable that the blast which is projected against the face be perfumed, and it is for this purpose that we provide the opening *c* in the upper head. Perfume may be introduced into the pump- 85 cylinder through this opening *c* and the opening then closed by the plug *c*'.

In operation it will be observed that when the operator presses down on the outer end of foot-lever *f*' the rod *f* is elevated, carrying 90 the lower head *c*'' upwardly, compressing the air in the cylinder, and forcing the same out through exit *d* and tube *e*. This upward movement which is imparted to the head *c*'' compresses spring *h*, and when the pressure of the 95

foot-lever f' is relieved the spring h forces the rod f and lower head c'' downwardly or to the normal position, and during such downward movement of the lower head c'' the flap-valve b'' rises to allow another supply of air to enter through port e' , the flap-valve closing immediately upon the lower head reaching its normal or rest position.

Having thus described our invention, what we claim as new, and desire to secure by Letters Patent, is—

The combination with the chair, of a drying attachment carried by the chair and comprising a bracket fixed to the chair and having a pair of outwardly-extending supporting-arms, and a downwardly-extending guide-arm, an air-forcing apparatus comprising a cylinder

mounted between the supporting-arms and having a movable lower head, a rod working through the lowermost supporting-arm and 20 the guide-arm and connected to said movable lower head, an air-inlet and an air-outlet for said cylinder, a flexible tube connected to the air-outlet, a foot-lever connected to the rod for operating the lower head to force air through 25 the outlet and tube, and a spring for returning the lower head to its normal or rest position.

In witness whereof we have hereunto set our hands this 6th day of June, 1900.

LEANDER P. BOWEN.
WILLIAM J. WHITE.
